UNITED STATES PATENT OFFICE.

EVA RACHLIN, OF BROOKLYN, NEW YORK.

GUTTER HANGER.

Application filed March 17, 1926. Serial No. 95,306.

The present invention relates to improvements in gutter hangers, and more particularly to that type which is commonly known in the trade as a "shank and circle" hanger.

5 The main object of the invention is to provide a gutter hanger of this type, the shank and circle of which are each stamped from a single piece of sheet metal and so formed and combined that rocking of the 10 circle on the shank is effectively prevented.

Another object of the invention is to so construct and design the circle that it may be made of comparatively thin stock and still be capable of withstanding the strains 15 and stresses to which it is subjected.

With these and other objects in view, which will more fully appear as the nature of the invention is better understood, the same consists in the combination, arrangement and construction of parts hereinafter described, pointed out in the appended 20 claim and illustrated in the accompanying drawings, it being understood that many changes may be made in the size and proportion of the several parts and details of construction within the scope of the appended 25 claim, without departing from the spirit or sacrificing any of the advantages of the invention.

30 One of the many possible embodiments of the invention is illustrated in the accompanying drawings, in which:—

Figure 1 is a side elevation of a gutter hanger constructed in accordance with the 35 present invention, the gutter being shown in position thereon; Fig. 2 is a section taken on line 2—2 of Fig. 1 on a larger scale; Fig. 3 is a section taken on line 3—3 of Fig. 1, also on a larger scale; Fig. 4 is a side elevation, on a larger scale, of the circle element 40 of the hanger, showing in dotted lines the blank from which it is formed; and Fig. 5 is a top plan view of a portion of the element shown in Fig. 4.

45 As appears from Figs. 1 to 3, inclusive, of the drawings, the hanger comprises a gutter supporting circle 10 and a shank 11, the elements being adjustably secured together by a screw-bolt 12, the shank being secured to 50 the supporting structure in any suitable manner, for instance by nails, not shown.

The gutter hanger circle is stamped from a single strip 13 of sheet metal, shown in dotted lines in Fig. 4 of the drawings. This 55 strip is rolled or bent edgewise into the shape of an arc of a circle to form a gutter

hanger circle. On the inner end of this circle is formed a finger or catch 15, for engagement with the plain edge 16 of the gutter 17. The outer end of the circle is 60 notched, to form a hook 18, which is adapted to be extended through an opening 19 in a hook-shaped element 20, that is capable of being bent over the bead 21 of the gutter, as shown in Fig. 1 of the drawings. The 65 heel portion 22 of the circle is bent out of the body portion of the latter, whereby a vertical shoulder 23 is formed at the junction of the said heel and body portions. The purpose of this arrangement will be described hereinafter. In the heel portion 22 of the circle is provided a vertical row of apertures 24, through which the screw bolt 12 is extended. In the rear face of the heel portion are formed two or more projections 70 25, which are adapted to be seated, as will 75 hereinafter appear, in a groove in the shank 11.

The shank is also, preferably, stamped from a single piece of sheet metal, it comprising a vertical stem 26 of conventional 80 channel formation. Throughout practically its extent, vertically considering, the shank is apertured, as at 27, so that the circle may be adjusted thereon in a well understood manner. When the elements of the hanger are being assembled, the projections 25 on the heel portion of the circle are seated in the channel of the stem of the shank, the shoulder 23 abutting throughout its length 90 against the inner longitudinal edge 28 of the stem, so that rocking of the circle on the shank is effectively prevented. From one side of the stem projects laterally a plate 29, provided with perforations 30. 95 This plate is shorter than the stem and serves as the means for attaching the shank to the supporting structure, the nails above mentioned passing through the perforations in the plate 29 into the supporting structure, such as a rafter or other member adjacent to a gutter or eaves-trough.

A plurality of shanks and circles, suitably spaced apart, are used for mounting the gutter on the supporting structure. In use, the shank is first attached to the supporting structure and the circle thereafter mounted thereon. The circle is shifted on the shank to the desired height and the screw bolt extended through registering apertures in the shank and circle. The gutter is then put in place, the hook-shaped elements 20 being en- 100 105 110 115

gaged with the gutter bead. It is to be noted that inasmuch as the circle is bent or rolled edgewise, in forming the same, the circle may be made of comparatively thin stock and yet be able to withstand the strain and stresses to which it is subjected.

It is obvious that, while herein a specific way has been described for attaching the shank to the supporting structure, any other ¹⁰ method may be employed without departing from the invention.

What I claim is:

A gutter hanger circle stamped from a single straight strip of sheet metal bent

edgewise into an arc of a circle and including a body portion and a heel portion, said heel portion being bent out of the plane of said body portion to form a vertical shoulder at the juncture of said body and heel portions, and said bent out heel portion being provided with a plurality of projections arranged in a vertical line and spaced from said shoulder.

Signed at New York, in the county of New York, and State of New York, this ²⁵ 20th day of February, A. D. 1926.

EVA RACHLIN.
